UNITED STATES PATENT OFFICE.

GEORG GLOCKEMEIER, OF LUDERITZBUCHT, SOUTH WEST PROTECTORATE, SOUTH AFRICA, ASSIGNOR TO CARL KRAUSE, OF LUDERITZBUCHT, SOUTH WEST PROTECTORATE, SOUTH AFRICA.

CONCENTRATING-JIG.

1,354,550.

Specification of Letters Patent.

Patented Oct. 5, 1920.

Application filed June 28, 1919. Serial No. 307,448.

To all whom it may concern:

Be it known that I, GEORG GLOCKEMEIER, citizen of South West Protectorate, South Africa, residing at Luderitzbucht, South 5 West Protectorate, South Africa, have invented certain new and useful Improvements in Concentrating-Jigs, of which the following is a specification.

The present invention relates to jig concentrating apparatus for recovering diamonds and other precious stones and ore concentrates; said apparatus being of the kind in which relative vertical reciprocation is brought about between a bed of the material carried on a sieve and a body of water in which it is immersed.

The present invention is based on the discovery that when the jig screen is curved or inclined the concentrate tends to rise to the 10 highest point of the screen instead of passing to the lowest point as has hitherto been thought. This phenomenon can be explained by the fact that the shape of the sieve causes the jig bed gradually to decrease in thickness at the higher part of the screen. The 15 water acting upwardly on the bed, finds least resistance toward such thin part of the bed. The stream of water, which is originally perfectly vertical, is thus diverted toward the highest point of the screen and the 20 concentrates,—being the heaviest particles, and therefore lying immediately on the screen,—are pushed forward in the direction of the highest point.

The present invention accordingly consists in the method of forming a jig bed of gradually varying thickness and discharging the concentrate at or near the thinnest point or zone of the bed.

The invention also consists in a jig having an inclined or curved screen, in which the means for feeding the jig material and the discharge orifices for the concentrates are disposed to take advantage of this rising 45 tendency of the concentrate. The invention also consists in the specific forms of sieve hereafter described.

In the accompanying drawings:

Figure I is a vertical section of a jig of the Schiechel type embodying the invention.

Fig. II is a plan of the screen drawn to a larger scale.

Figs. III and IV are sectional elevations

taken at right angles to one another of a 55 rectangular screen suitable for a Hartz jig.

Referring first to Figs. I and II, 1 is the screen mounted on a frame 2 and supported in dome form by ribbing 3, 3^a.

The sieve is carried at the top of a chamber 4 communicating with an annular chamber 5 closed at the top. Said chambers 4 and 5 contain water to about the level of the sieve; and pulsation of the water in chamber 4 is brought about by pulsations of the air 60 contained above the water in chamber 5.

Such pulsations of the water concentrate the jig material lying on the screen. The tailings pass over the lip of the sieve into the space 6 and are discharged through the 70 opening 7. The concentrates pass through discharge holes 8 in the screen and collect in the hopper 9 whence they are discharged in any suitable manner.

In order to embody the present invention 75 in this jig the discharge holes in the screen are arranged at the highest point consistent with properly feeding the jig material and the feed is arranged to interfere as little as possible with the rising movement of the 80 concentrate. Accordingly the feed spout 10 is arranged to deliver the material onto a restricted area at the center of the sieve. The discharge holes are arranged, as appears in Fig. II, in a circle at such a distance from 85 the center that the pressure of the feed ceases materially to interfere with the climbing tendency of the concentrate.

The supporting frame on which the sieve mesh rests is arranged to interfere as little 90 as possible with the direct action of the water on the jig bed. The members 3 of the supporting ribbing are radial; and where an annular member 3^a is employed it is placed within the zone of the discharge openings 8. 95 This feature is of importance in the successful operation of the sieve since the proper movement of concentrate lying on the sieve depends upon the direct pressure of water upon it. If for instance the annular member 3^a were placed outside the ring of holes 8, it would form a barrier past which the concentrate could be moved only with great difficulty. In cases where it is necessary to provide supports crossing the line of march of 100 the concentrate, some space should be left between them and the sieve mesh.

Rigid dome sieves such as that illustrated are already used in connection with Schiechel jigs, but the concentrate discharge openings have been formed at or near 5 the lowest point and the feed has been distributed over a large area at the center. Moreover in hand jigs and Schiechel separators a central discharge has been used in the so called "stretched" sieve which is not 10 provided with supporting ribs and consequently oscillates in the center with the pulsations of the water or the sieve frame. It was believed that the concentrates went to the center of the stretched sieve because this 15 was the deepest point in the suction phase. While therefore the discharge orifice was positioned in the center, the jig material was fed to an annular zone half way between the edge of the sieve and the center. The result 20 was that the fresh material formed a barrier which the concentrates could only pass with difficulty on their way to the discharge. The output of such a sieve is materially increased by modifying it in accordance with 25 this invention.

Figs. III and IV illustrate an application of the invention to a sieve for a jig of the Hartz type in which the sieve is rectangular, the jig material being fed at one end 11 and the tailings being discharged at the other 30 end 12.

In this case the sieve is curved or inclined upwardly from both sides to the middle longitudinal line 13. The supporting ribs 3 are

arranged transversely to the length of the 35 sieve. Concentrates mount to the central ridge of the sieve and are carried by the general longitudinal movement of the whole material to the concentrate discharge spout 14, 15 which is situated on the central line 40 and near the discharge end 12. The discharge spout consists of a fixed tube 14 and a tube 15 revoluble therein. Said tubes are formed with corresponding apertures 16, through which the concentrate passes away. 45 By rotating the tube 15 the size of the discharge opening can be regulated.

I claim—

1. A jig sieve having sloping sides and a raised central portion provided with concentrate discharge openings in proximity to its 50 highest point.

2. In a jig, an upwardly domed sieve having concentrate discharge openings in an annular zone near to the center, and a feed device arranged to feed jig material to a restricted area in the center of the sieve. 55

3. A rigid jig sieve including a convex screen body having a circle of concentrate discharge openings near the center, a supporting rim at the outer edge of the screen body, a reinforcing ring secured to the screen body and positioned within the circle of openings and radial ribs between the ring and the rim. 60

In testimony whereof I affix my signature.

GEORG GLOCKEMEIER.
